GEORGE H. GILBERT, OF GERMANTOWN, PENNSYLVANIA.

CAR-COUPLING.

1,126,979.

Specification of Letters Patent.

Patented Feb. 2, 1915.

Application filed August 6, 1914. Serial No. 855,386.

To all whom it may concern:

Be it known that I, GEORGE H. GILBERT, a citizen of the United States, residing at Germantown, in the county of Philadelphia and State of Pennsylvania, have invented 5 certain new and useful Improvements in Car-Couplings; and I do hereby declare the following to be a full, clear, and exact description of the invention, such as will enable others skilled in the art to which it 10 appertains to make and use the same.

My invention consists in the novel features hereinafter described, reference being had to the accompanying drawing which 15 illustrates several forms in which I have contemplated embodying the same, and which I have selected for purposes of illustration, and my said invention is fully disclosed in the following description and 20 claims.

Referring to the said drawings: Figure 1 represents a diagrammatic plan view of the adjacent ends of two railway cars of a train, and showing each car provided with my improved coupling, the cars being represented 25 as being at the intersection of a straight portion of the track with a curve, and one car being located on the straight portion and the adjacent car on the curve. Fig. 2 represents a vertical transverse sectional view through one of the couplings shown in 30 Fig. 1 on the dotted line 2—2 looking in the direction of the arrows in that figure. Fig. 3 represents a longitudinal sectional view of 35 a coupling embodying my invention on the dotted line 3—3 of Fig. 2 looking in the direction of the arrows in that figure. Figs. 4, 5, and 6 are views similar to Fig. 3, illustrating slightly modified forms of 40 my improved coupling.

In the operation of railway trains connected by standard couplings of the jaw type now in use, the shanks of the coupling heads are rectangular in cross section and 45 are held between rectangular surfaces so that no provision is made for independent torsional movement between the coupler heads of the engaged couplings, or between the coupling and the car or vehicle with 50 which they are connected. In laying the curved portions of railway tracks, the road bed is "banked" on the outer side of the curve and inclined from the inside upwardly, the outer rail being higher than the inner rail, and both rails being substantially perpendicular to the inclined road bed. 55

When a train of cars is on a curved section of track the longitudinal axis of each car is disposed angularly with respect to the longitudinal axes of the adjacent cars, 60 and in passing around a curve the center of gravity is shifted from a vertical longitudinal plane centrally between the rails to a position between the center and the inner rail of the curve throwing an extra amount 65 of weight on the wheels on the inner rail and taking a corresponding amount of weight from the wheels on the outer rail. It therefore follows that as a train of cars enters upon a curve the locomotive will be 70 inclined toward the inner side of the curve, while the tender and following cars are still upon the straight and comparatively level track, thus producing a torsional strain on the couplings between the engine and tender and subsequently on the couplings between 75 all of the following cars as they enter the curve. While the train is rounding a curve each car will assume a position angular to those forward and in rear of it and 80 will also incline toward the inner side of the curve, and as the train leaves a curve and enters upon a straight portion of the track the locomotive will first resume a vertical position followed successively by the 85 remaining cars. Hence in entering, rounding, and leaving a curve, the couplings between the separate cars will be subjected to a severe twisting or torsional strain, which is transmitted to the bodies of the cars with 90 which they are connected and from one car to the adjacent car or cars by the rectangular coupler shanks and rectangular apertures in which they are held. These torsional strains so transmitted through the 95 couplings frequently have the effect of causing derailment, as, for example, where a relatively light car following a locomotive or a heavier car is tilted beyond any position it would normally assume, by the 100 weight of the heavier car or locomotive exerted through the couplings and which tends to overturn the lighter car or raise some of its wheels from the rails. Such an accident may, and has resulted, where 105 the cars were moving even at slow speed, and in taking curves at high speed conditions may easily arise where the lateral inclination of the locomotive or an adjacent car exerts a twisting or torsional stress 110 upon an adjacent car or cars which may result in lifting some of the wheels from

the rail causing derailment, or in actually overturning the car.

My invention has for its object the overcoming of this objectionable and dangerous condition by providing the locomotive and cars of a train with couplings so constructed as to permit entire freedom of movement in a rotary direction between the car body and the draw bars or couplings, so as to preclude the possibility of torsional strain or stress being exerted from the locomotive or one car to another car, and to permit each unit of the train connected by such couplings to independently take such inclined positions as the road bed and the speed and mass of the car tends to produce without affecting in any way the position of the adjacent car or cars, and relieving the couplings throughout the entire train of torsional stress. I also prefer to provide the couplings with yielding means which tend to hold the coupler heads in normal position with respect to the car for coupling purposes, but without being of sufficient strength to exert any appreciable torsional strain on the car body, while permitting the car to freely twist or partially rotate on the longitudinal axis of the coupler shank and draw bar, in either direction, the coupler shank and draw bar remaining at all times in substantially normal position.

In carrying out my invention it is essential that the coupler head or the draw bar shall be connected to the railway vehicle by what is practically a swivel joint, the axis of which extends longitudinally of the vehicle, so that a perfectly free movement in a rotary direction around such axis of swiveling may take place between the coupling and the vehicle.

In Figs. 1, 2 and 3 of the accompanying drawing, I have shown my invention embodied in a car coupling of known general construction but so modified as to embody my invention and effect its novel results.

In Fig. 1 I have shown in dotted lines two cars of a train at A and B connected by my improved couplings, and, as the couplings are identical in structure, a description of one will suffice for both. In this form of coupling, 1 represents a metallic frame formed of side bars, 2—2, and spacing blocks 3, 3, constituting a frame suitable to be attached to the under side of the car body and support the mechanism of the coupling. 4 represents a longitudinally disposed draw bar provided with cylindrical portions which engage cylindrical bearings in the spacing blocks 3, 3, so that it can be readily rotated therein in either direction, said draw bar being provided centrally between said bearings with the boss or collar 5, and being also provided with the usual cushioning or compression springs 6—7, between said boss and the spacing blocks. The forward end of the

draw bar is provided in this instance with a bifurcated portion 8, which receives the reduced end of the shank 9, of the coupler head to which it is secured by a pivotal connection 10. The shank 9 is provided with a coupler head 11, which may be of any well known or preferred construction, and, as the specific construction of this coupler head forms no part of my present invention, I will not specifically describe the same. It is necessary that the coupler heads shall move laterally in swinging around curves and the pivotal connection 10 between the shank— and the draw bar permits the lateral swing of the coupler head in either direction, while, as before stated, the coupler head can be rotated in either direction as the draw bar is swiveled in the manner previously described in its bearings in the spacing blocks 3, 3.

In order to hold the coupler head 11, in a central position and also in a normal or horizontal position torsionally to facilitate coupling when cars are brought together to be coupled, I have shown, in the form of my invention illustrated in Figs. 1, 2, and 3, the following mechanism, although I do not limit myself thereto. In this instance, the shank 9, of the coupler head is provided with a vertically disposed boss, or block 12, which extends above and below the shank and is preferably provided with vertically disposed plane lateral faces. On opposite sides of the boss 12, are provided laterally yielding vertically disposed pressure plates 13, 13, each of which is provided in this instance with a pair of supporting studs, 14, having reduced portions 15, extending into recesses in the supporting frame 1, in this instance formed in blocks 16, 16, secured to the side frames 2, 2, by screws or bolts, the said studs being provided at their outer ends with threaded portions provided with nuts 17. Within the recesses in the blocks 16 are provided light springs 18, interposed between the ends of the recesses and the shoulders of the studs, which tend to normally hold the plates 13 in engagement with the opposite sides of the boss 12, thus serving two functions, to wit: holding the coupler head 11 centrally with respect to the car or vehicle, and also horizontally so that two cars can be readily brought together and coupled in the usual manner. It will be obvious that the coupler head may be moved laterally to the right or left, thereby compressing one or the other set of springs 18, and it will also be apparent that, as indicated in dotted lines in Fig. 2, the car can assume any desired angular position about the axis of the coupler head without causing any rotation of the coupler head, which always remains in its normal position. When the car rocks with respect to the longitudinal axis of the coupling the plates 13 will recede, one being pressed outwardly by the upper end of the

boss and the other being pressed outwardly by the lower end. The springs 18 are merely sufficient to maintain the coupler head and the car in proper relation for coupling. It 5 will be noted that the springs of each lateral pressure plate are located one above and the other below the longitudinal axis of the shank, as shown and this provides the most efficient construction for maintaining the 10 coupler head in normal position against lateral and torsional movement.

In using my coupling each car of a train is entirely free to incline transversely to accommodate the road bed over which it is 15 passing without affecting the couplings between it and the next adjacent car or cars and without exerting any torsional stress on adjacent cars. Thus in Fig. 1 car A is shown as being on a straightway portion of the 20 track while the car B is on the curved portion of the track, the outer rail of which is higher than the inner rail. The car B will obviously be tilted inwardly, as indicated in the drawing, thus tilting the coupling frame 25 1, while the coupler head itself remains in substantially the same position it would occupy if the car had not listed. It will be noted that in the case of car A the inner spring actuated pressure plate 13 has yielded 30 to accommodate the movement of the coupler head laterally while in the case of car B both plates 13 have yielded to accommodate both the lateral swing of the coupler head and a torsional displacement between the two cars.

35 In Fig. 4 I have shown a slight modification of my invention, in which the construction is exactly the same as that previously described except that the boss here indicated at 12^a is located upon the draw bar 4^a instead of being located on the shank of the coupler head as in Figs. 1, 2, and 3, the plates 13 (which do not show in this figure) being located in line with the boss 12^a and acting in conjunction therewith exactly in 45 the same manner as indicated in Fig. 2.

In Fig. 5 I have shown a slight modification of my invention, in which the boss 12 and yielding pressure plates 13, 13, and their connections are dispensed with. In 50 this construction the draw bar 4^b is cylindrical and mounted in cylindrical bearings as in the other figures previously described, and is provided with the central collar or boss 5^b and the cushioning or compression springs 6^b and 7^b have their ends constructed to engage the boss 5^b and one of the bearing blocks or spacing blocks 3^b respectively, as clearly shown in Fig. 5, so that the springs perform both the compressing 55 cushioning function and also the function of holding the coupler head in its normal position for coupling. The coupler head 11^b is provided in this instance with a plain shank 9^b and if found desirable suitable 60 cross plates 20, 20 may be inserted between

the side plates 2^a of the frame 1^a to prevent vertical displacement of the coupler head as indicated in Fig. 5. These plates, however, will not interfere with the lateral movement of or rotation of the shank, which is 70 cylindrical in shape, or, in other words, circular in cross section.

In Fig. 6 I have shown another modification of my improved coupling in which the draw bar 4^c is also circular in cross section 75 and mounted in cylindrical bearings in the spacing blocks 3^c interposed between the side plates 2^c of the supporting frame 1^c. In this instance I have shown the draw bar provided with a central boss 5^c having at 80 each end thereof annular portions of reduced diameter forming shoulders 21 and the spacing blocks 3^c are provided with similar shoulders 22 on their inner faces. In this instance I have shown light spiral 85 springs 23, 23 interposed between the shoulders 21 and 22 and having their ends connected thereto for the purpose of maintaining the coupler head in normal position with respect to the car, for coupling. And 90 I have shown heavier cushioning or compression springs 6^c and 7^c, interposed between the boss 5^c and the bearing blocks 3^c and surrounding the shoulders 21, 22, for cushioning the draw bar in both directions 95 longitudinally. In this instance also the coupler head 11^c is provided with a plain cylindrical shank 9^c held against vertical movements by the guiding plates 20^c, 20^c.

In all the forms of the invention herein 100 shown and described, it will be seen that while the coupler head is free to move laterally, it is at all times capable of twisting or swiveling with respect to the car body with which it is connected, so that the car 105 body may assume different angular positions without affecting the coupler head and without transmitting torsional stress to an adjacent car or unit of the train, suitable yielding means being provided as before 110 stated, to maintain the coupler head in its normal position for coupling.

What I claim and desire to secure by Letters Patent is:—

1. The combination with a railway vehicle, of a coupler head provided at its outer end with a coupling jaw adapted to automatically couple with the corresponding jaw of the coupler head of another vehicle without torsional movement and constructed to prevent torsional movement 115 between it and the jaw which it engages, and connections between the coupler head and the vehicle constructed to permit at all times longitudinal yielding movement in 120 both directions of the coupler head and lateral movement of the coupler head, said connections being constructed to permit free torsional movement at all times between the coupler head and the vehicle, 125 130

- whereby the vehicle is free at all times to take any transverse inclination without transmitting torsional strain to the coupler head or to another vehicle with which it may be coupled.
2. The combination with a railway vehicle, of a coupler head provided at its outer end with a coupling jaw adapted to automatically couple with the corresponding jaw of the coupler head of another vehicle without torsional movement and constructed to prevent torsional movement between it and the jaw which it engages, and connections between the coupler head and the vehicle constructed to permit at all times longitudinal yielding movement in both directions of the coupler head and lateral movement of the coupler head, said connections being constructed to permit free torsional movement at all times between the coupler head and the vehicle, whereby the vehicle is free at all times to take any transverse inclination without transmitting torsional strain to the coupler head or to another vehicle with which it may be coupled, and yielding means interposed between the coupler head and the vehicle for normally maintaining the coupler head in a predetermined relation with the vehicle to facilitate coupling.
3. The combination with a coupler head provided at its outer end with a coupling jaw adapted to automatically engage with and couple to the corresponding jaw of the coupling head of an adjacent vehicle without torsional movement of the coupler head and constructed to prevent torsional movement between it and the jaw which it engages, a longitudinally movable draw bar having a vertical pivotal connection with the coupler head to permit the lateral movement of the coupler head, connections between the draw bar and the vehicle including springs for cushioning the longitudinal movement of the draw bar in both directions, said draw bar being swiveled longitudinally with respect to said connections, and yielding devices interposed between the vehicle and parts connected with the coupler head for normally maintaining the coupler head in a predetermined position torsionally with respect to the vehicle to facilitate coupling, whereby the vehicle is free at all times to take any transverse inclination without transmitting torsional strain to the coupler head or to another vehicle with which it may be coupled.
4. The combination with a railway vehicle of a coupler head, draft mechanism connecting the same with the vehicle and constructed to permit the coupler head to move freely with respect to the vehicle in a rotary direction, yielding mechanism for maintaining the coupler head in a predetermined position torsionally with respect to the vehicle, and comprising a part extending transversely from a part connected with the coupler head and movable in a rotary direction therewith, and a spring actuated part adapted to engage said laterally extending part.
5. The combination with a railway vehicle of a coupler head, draft mechanism connected to the vehicle and to said coupler head and including a rotarily mounted part disposed longitudinally with respect to the vehicle and operatively connected with said coupler head, a boss connected with said rotarily mounted part and having portions extending at opposite sides of the same; and yielding plates located on opposite sides of said boss for maintaining said coupler head in a predetermined position torsionally with reference to the vehicle.
6. The combination with a railway vehicle of a draft frame, a longitudinally disposed draw bar mounted therein and capable of rotation about its longitudinal axis, cushioning devices engaging said draw bar, a coupler head connected with said draw bar and capable of rotary movement with the draw bar with respect to the vehicle, said coupler head having a shank provided with projecting portions extending above and below the same, and laterally disposed yielding plates on opposite sides of said projecting portions, for maintaining the coupler head in normal position for coupling.
7. The combination with a railway vehicle, of a draft frame, a longitudinally disposed draw bar mounted therein and capable of rotation about its longitudinal axis, cushioning devices engaging said draw bar, a coupler head connected with said draw bar and capable of rotary movement with the draw bar with respect to the vehicle, said coupler head having a shank provided with projecting portions extending above and below the same, and laterally disposed yielding plates on opposite sides of said projecting portions, each of said plates being provided with springs above and below the axis of said shank, whereby the coupler will be maintained normally in a predetermined position against lateral and torsional movement with respect to the vehicle.
8. The combination with a railway vehicle of a draft frame, a longitudinally disposed drawbar mounted therein and capable of rotation about its longitudinal axis, and of longitudinal movement with respect to said frame, springs operatively connected with said drawbar for cushioning its longitudinal movement in both directions, a coupler head connected with said drawbar by a pivotal connection having a vertical axis, to permit the free lateral movement at all times of the coupler head, said coupler head being constructed to couple with the coupler

- head of another vehicle, without torsional movement, and constructed to prevent torsional movement between it and the engaged coupler head, whereby the vehicle is free to take any transverse inclination without transmitting torsional strain to the coupler head or to another vehicle, or interfering with the freedom of lateral movement of the coupler head.
- 10 9. The combination with a railway vehicle, of a draft frame, a longitudinally disposed drawbar mounted therein and capable of rotation about its longitudinal axis, and of longitudinal movement with respect of the frame, cushioning springs interposed between the frame and said drawbar for cushioning its longitudinal movement in both directions, a coupler head connected with said drawbar by a pivotal connection having a vertical axis, to permit the lateral

movement of the coupler head, said coupler head being constructed to couple with the coupler head of another vehicle without torsional movement, and constructed to prevent torsional movement between it and the engaged coupler head, and yielding devices operatively connected with said coupler head for maintaining the coupler head in normal relation torsionally with respect to the vehicle, to facilitate coupling without interfering with the torsional movement of the vehicle with respect to the coupler head and drawbar or the lateral movement of the coupler head.

In testimony whereof I affix my signature, 35
in the presence of two witnesses.
